Primary Examiner — Dana L Meyrow(74) Attorney, Agent, or Firm — Lowenstein Sandler LLP(57) CLAIM

The ornamental design for a bottle, as shown and described.

DESCRIPTION

FIG. 1 is a perspective view of a bottle showing our new design;

FIG. 2 is a right side elevation view thereof, the left side elevation view being identical;

FIG. 3 is a front elevation view thereof, the rear elevation view being identical;

FIG. 4 is a top plan view thereof; and,

FIG. 5 is a bottom plan view thereof.

The broken lines in the drawings illustrate portions of the bottle that form no part of the claimed design.
